UNITED STATES PATENT OFFICE.

JAMES THOMSON, JR., OF PAWTUCKET, RHODE ISLAND, ASSIGNOR TO THE THOMSON MANUFACTURING COMPANY, OF PROVIDENCE, RHODE ISLAND.

DESIGN FOR A ROTARY CLEARING-DISK.

SPECIFICATION forming part of Design No. 27,895, dated November 23, 1897.

Application filed April 28, 1897. Serial No. 634,299. Term of patent 14 years.

To all whom it may concern:

Be it known that I, JAMES THOMSON, Jr., a citizen of the United States, residing at Pawtucket, in the State of Rhode Island, have invented and produced a new and original Design for a Rotary Clearing-Disk for the Drawing-Rolls of Cotton Machinery, of which the following is a specification, reference being had to the accompanying drawings, forming 10 a part thereof.

In the accompanying drawings, Figure 1 represents a sectional view of a rotary clearing-disk, showing my new design. Fig. 2 represents a face view of the same.

15 My design for a rotary clearing-disk for the drawing-rolls of cotton machinery consists in the hollowed concavous form of the bearing

side of the disk within an annular plane surface and in the fibrous appearance of the side of the disk.

20 In the drawings, A represents a rotary clearing-disk, the bearing side *a* of which is hollowed concavously in shallow form within an annular plane surface *b*, and also has a fibrous appearance at both its concavous and 25 plane surfaces, as indicated in the drawings.

What I claim is—

The design for a rotary clearing-disk substantially as herein shown and described.

JAMES THOMSON, JR.
